UNITED STATES PATENT OFFICE.

BERNICE J. NOYES, OF BOSTON, MASSACHUSETTS, ASSIGNOR TO GEORGE W. GREGORY, OF SAME PLACE.

SIGNAL-BOX.

SPECIFICATION forming part of Letters Patent No. 533,014, dated January 22, 1895.

Application filed May 27, 1892. Serial No. 434,635. (No model.)

To all whom it may concern:

Be it known that I, BERNICE J. NOYES, of Boston, county of Suffolk, State of Massachusetts, have invented an Improvement in 5 Signal-Boxes, of which the following description, in connection with the accompanying drawings, is a specification, like letters on the drawings representing like parts.

Prior to this invention signal boxes have 10 been provided with local alarms which are sounded when the latch, or knob of the door of the box is turned, or when a glass fitted in the front of the box is broken, to render accessible the pull or hook by means of which 15 the signal transmitter is operated. The person pulling in the alarm is sometimes deceived by the local alarm, presuming that when sounding, the fire alarm or signal is being transmitted, although such boxes have 20 been plainly marked.

This invention has for its object to provide a signal box containing any suitable alarm, or signal transmitting apparatus, with a local 25 alarm operating mechanism adapted to be automatically let off, or operated when the door of the box is opened or a glass fitted in the front of the box is broken, and to simultaneously let off, or operate the signal transmitter, so that whenever said local alarm is 30 sounded the transmitter will be automatically operated, and the signal transmitted, without requiring the person at the box to pull the hook after opening the door, or after said local alarm has sounded, or during the time it is 35 sounding.

This invention may be carried out in many different ways, but as herein shown the signal transmitting apparatus, and also the local alarm operating mechanism, both comprise 40 normally wound motors, which when released, operate to perform their respective duties, yet said motors may be normally unwound, and the operating parts so connected together that when the local alarm is operated, the 45 signal transmitting apparatus will also be operated.

Figure 1, shows in front elevation, a signal transmitting apparatus and local alarm operating mechanism, and intermediate connection between them, whereby the signal transmitter and local alarm operating mechanism,

are both set in operation by the act of opening the door, said parts being removed from their inclosing box or case; Fig. 2, a detail of the let off or releasing device; Fig. 3, a front elevation of the signal box with the door opened, and Fig. 4, a front elevation of the box with the door closed; Fig. 5, a detail to be referred to.

The signal transmitting apparatus herein 50 shown consists of a suitable frame, a toothed driving wheel a , mounted on the winding shaft a' , journaled in said frame and carrying a pawl a^2 , which engages a ratchet wheel a^3 , secured to said shaft.

The wheel a , engages a pinion a^4 , on a shaft carrying a toothed wheel a^5 , which latter engages a pinion a^6 , secured to a shaft carrying an escape wheel a^7 , with which co-operates the pallet a^8 .

The signal wheel a^9 , is secured to the shaft carrying the toothed wheel a^5 , and suitable contact pens a^{10} are provided which engage said signal wheel.

The wheel a^5 , carries a stop pin a^{12} , which 75 enters a notch in a locking lever a^{13} , pivoted to the frame at a^{14} , and carrying a pin a^{15} , which enters a recess between the ends of flanges a^{16} , a^{17} , on the wheel a , when the train is at rest, and which bears upon one or the 80 other flange when the train is in motion, to thereby keep the locking lever in elevated position while the signal wheel a^9 , is making several revolutions.

A hook or pull b , is provided, which is 85 adapted to lift one end of the locking lever a^{13} , to release the train.

This form of signal transmitting apparatus is well known, but in lieu of it, any other well known form may be employed.

The local alarm mechanism comprises a gong c , adapted to be struck by the hammers c' , on the pallet c^2 , of the normally wound train, consisting of the toothed driving wheel c^3 , mounted on the winding shaft c^4 , and connected therewith by the pawl and ratchet in the usual manner, a pinion c^5 , engaged by said toothed wheel c^3 , a toothed wheel c^6 , secured to the shaft carrying said pinion, and the pinion c^7 , engaged by said toothed wheel, 95 and secured to a shaft carrying an escape wheel c^8 , with which said pallet c^2 , co-operates.

A projection c^9 is secured to the pallet c^2 which is engaged by one arm of a bell crank lever c^{10} , see Fig. 2, pivoted at c^{12} , the other arm of said lever normally bearing against a plate of glass c^{13} , fitted in the door c^{15} , or it may be against the door c^{15} itself, the glass plate not being employed.

A rock shaft d , is mounted in suitable bearings, having at one end a short arm d' , Fig. 5, which terminates just beneath the end of the locking lever a^{13} , and has at its other end a short arm d^2 , which is connected by a link d^3 , with one arm of the bell crank lever c^{10} . The short arm d' , is made of suitable length 15 so that when raised to lift the locking lever, the latter slips off, or is disengaged, and on the end of said arm a small block d^x is hinged which permits the arm to pass beneath the locking lever, thereby resuming its normal 20 position.

The operation is as follows:—When the door c^{15} , is opened, or when the glass plate c^{13} , is broken, the bell crank lever c^{10} , is released, letting off the local alarm train, which causes 25 the pallet c^2 , to move the hammers, and strike the gong, and at the same time that said bell crank lever c^{10} , is released, the shaft d is rocked moving the locking lever a^{13} , and releasing the signaling train, so that it will be 30 seen that whenever the glass is broken or the door opened and the local alarm operated the signal will be transmitted. The door c^{15} , is not provided with a lock, but simply with a latch, which is operated by the handle e , 35 that said door may be opened without the aid of a key, and hence the box resembles what is commonly known as a keyless box. The glass plate is inserted in the door for the reason that many people can readily understand that to send an alarm they must break 40 the glass, but as above implied said glass plate may be omitted.

Instead of employing the particular construction shown of intermediate mechanism connecting the two trains, any other form 45 may be employed, and furthermore instead of connecting the releasing or operating lever of the signaling train, with the releasing or operating lever c^{10} , or with the local alarm it may 50 be operated independently by breaking the glass or opening the door. The box is also provided with a door c^{14} , by which access may be had thereto, and a slide bolt c^{20} , is arranged 55 on the inner door c^{21} , which when moved in one direction passes beneath a pin c^{22} , moving in a slot c^{23} , and secured to the link d^3 , so that the trains may be held at rest while the doors c^{15} and c^{25} , are opened for inspection, and on 60 the inner door c^{25} , a similar slide bolt c^{26} is arranged which when moved in one direction passes beneath the lever c^{10} , to hold the trains while the door c^{21} , is being opened for inspec-

tion, but in lieu of these particular locking devices any other equivalent forms may be employed.

65

I claim—

1. A signal box provided with a door, a signal transmitting apparatus, and a local alarm mechanism in said box the operating levers of both of which are automatically moved to 7c operate their respective apparatus and mechanism by opening of said door, substantially as described.

2. In a signal box, a signal transmitting apparatus, and a local alarm mechanism, the 75 operating levers of both of which are simultaneously and automatically moved by the breaking or removal of a removable front plate, substantially as described.

3. In a signal box, a signal transmitting 80 mechanism, and a local alarm mechanism, combined with a keyless door for controlling the operating levers of said mechanisms, and a locking device to positively lock said mechanisms when the said door is open for purposes of test, &c., substantially as described. 85

4. In a signal box, a signal transmitting mechanism, and a local alarm mechanism, and two inner doors c^{21} , and c^{25} , and locking devices thereon for said mechanisms combined with two outer doors c^{14} , c^{15} , the latter being keyless, and controlling the operating 90 levers of said mechanisms, substantially as described.

5. In a signal box, a signal transmitting apparatus, and a local alarm operating mechanism, the operating lever of which is controlled 95 by a removable front plate, and connections between said local alarm operating mechanism and the signaling train, whereby the latter is operated by the former, substantially as described.

6. In a signal box, a signal transmitting mechanism, and a normally wound local alarm mechanism, the releasing lever of which is 105 held by a removable front plate, and interposed connections between said mechanisms, whereby the signal transmitting mechanism is operated by the local alarm mechanism, substantially as described. 110

7. In a signal box, a signal transmitting mechanism, and a normally wound local alarm mechanism, the releasing lever of which is held by a removable front plate, the rock shaft d and arms d' , d^2 , and link d^3 , connecting the 115 arm d^2 , with the local alarm mechanism, substantially as described.

In testimony whereof I have signed my name to this specification in the presence of two subscribing witnesses.
